CONTAINER TOP SELECTING AND
DELIVERING MECHANISM

William R. Courtney, Chicago, Ill.

Application June 26, 1950, Serial No. 179,675

5 Claims. (Cl. 226—88.1)

1

Many mechanisms have been devised and successfully used in the past for selecting and delivering, in proper position, tops, or closures, for preformed containers. My invention is devised to select and deliver to a proper position a top, or closure, to cover, and subsequently seal a container which has been preformed, and preferably filled by the teachings described and claimed in my copending application filed on August 10, 1950, Ser. No. 179,678.

An object of my invention is to provide a mechanism to select a top or cover and place the same in proper position on a container to be sealed.

A further object is to provide a mechanism adapted to select a top or cover from a source of supply, remove the same from the source of supply and place the cover in proper position on a container to be sealed.

A still further object is to provide a swinging arm adapted to select a cover and place the same on a container to be sealed.

An even further object is to provide a swinging selector arm coordinated with a container conveyor and adapted to synchronously select and deliver a top onto a container conveyed into receiving position.

In the accompanying drawings:

Fig. 1 is a view in end elevation of the package top or closure selector;

Fig. 2 is a view in side elevation of the same;

Fig. 3 is an enlarged, view in vertical cross-section (partly broken away) through the selector suction cup, showing a top being selected;

Fig. 4 is a vertical cross-section on the line IV—IV of Fig. 3;

Fig. 5 is an enlarged view in vertical cross-section through the top or closure selector; and

Fig. 6 is a fragmentary vertical cross-section taken on the line VI—VI of Fig. 5.

The top selecting mechanism herein disclosed is adapted more particularly for use in combination with my container selecting and filling mechanism for which a patent application is filed concurrently herewith. The top selecting and delivery mechanism may, however, be equally well utilized in conjunction with any machine which presents a container to a predetermined position to have a top or closure placed thereon.

A container 78 is conveyed by suitable conveyor or chains 70 and 72 which are preferably operated in a step-by-step manner so that the platform 74, on which the container is held, will stop and be maintained at a predetermined point. While the container 78 is maintained at its pre-

2

determined point, the delivery arm 10 assumes the position in which it is shown in the figures and places a top or closure 12 in proper position thereon.

5 The delivery arm 10 is adapted to be pivotally supported by a horizontal, and hollow, arm 14 which is fixedly secured to, and extends outwardly at right angles from, a vertical and hollow post 16. The hollow post 16 stands vertically above, and is secured to, a table or platform A which is adapted to serve as a work bench to which the instant mechanism, and that disclosed in my copending applications Ser. Nos. 179,678; 179,676; and 179,677 (and now abandoned) are secured. The arm 16 is positioned to extend substantially parallel over the work bench or platform A.

Within the post 16 a vertically positioned rod 18 is slidably supported and is urged downwardly by a suitable coil spring 20. The spring 20 continually urges the rod 18 downwardly, maintaining the roller 22 secured thereto, into contact with a cam 24 keyed to the shaft 34.

On the end of the rod 18 remote from the roller 22, and above the table or platform A, I secure a rack bar 26 which is adapted to mesh with the rack gear 28 keyed to the shaft 30 extending through the arm 14. The end of the shaft 30 remote from the rack gear 28 is suitably secured within the delivery arm 10 by a set screw 32. By the revolution of the shaft 34, the cam 24 is revolved, and at the time that its high lobe assumes an upper position, the rod 18 will have been forced upwardly, and consequently its rack bar 26 will have revolved the rack gear 28 and its shaft 30, which latter will swing the arm 10 upwardly, as indicated by the arrows in Fig. 2.

The delivery arm 10 is hollow and is attached 40 to a suitable tube 36 extending to a vacuum which may be applied by suitable mechanism at the time that the arm is in its uppermost position, it having been swung thereto by the rotation of the shaft 30. Within the arm 10 at the 45 end thereof remote from its connection to the end of the shaft 30, a suitable hollow bell shaped cup 38, preferably of rubber or other pliable material, is secured and is urged gently into the position in which it is shown by the spring 39.

At the time that the shaft 34 has revolved so that the high lobe of the cam 24 has urged the rod 18 upwardly, and consequently the rack bar 26 has revolved the rack gear 28, and its attached shaft 30, the cup 38 will have been swung 55 upwardly to be in a position beneath a supply

chute 40 in which a supply of tops 12 are stacked. The tops 12 are frictionally held within the chute 40 by suitable balls or knobs 42 secured to the ends of shafts 44 which are spring urged inwardly to maintain the tops 12 within the chute 40, and to prevent their dropping out by gravity.

At the time that the arm 10 is swung upwardly, the cup 38 will come into contact with the bottommost top 12 within the chute 40, and simultaneously a vacuum will be applied through the vacuum tube 36. Subsequently, as the shaft 34 continues to revolve and the cam 24 is revolved so that the roller 22 will bear against the low lobe thereof, the rod 18 will descend by the pressure of the spring 20. Consequently, the shaft 34 will be rotated in the opposite direction, returning the cup 38 to the position in which it is shown in Figs. 1, 2 and 5.

When the arm 10 is in that position, a top 12 has been properly seated upon a container 78, and simultaneously with its being thus seated, the vacuum within the tube 36 is broken and the container with its properly seated top is then in a condition to be advanced by the step-by-step motion of the conveyor chains 70 and 72.

It will be understood that the step-by-step motion of the conveyor chains 70 and 72, with their attached platform 14, will be synchronized with the revolution of the shaft 34, its keyed cam 24 and associated mechanism. Hence at the time that the roller 22 is on the low lobe of the cam 24, a container 78 will have been stopped in position to receive a top 12 which is delivered by the downward swing of the arm 10. As the conveyor chains 70 and 72 advance in their step-by-step motion, the arm 10 will be swung upwardly, as described above, and another top 12 will be drawn by vacuum onto the cup 38, after which time the arm 10 will be swung downwardly in proper synchronous motion so that the selected top will be placed on a waiting container 78.

The operation, as described above, will continue synchronously with the mechanisms described in my copending applications, Ser. Nos. 179,678; 179,676; and 179,677 to repeatedly place a top on a container, which has been filled, so that the same may be further advanced by a step-by-step motion to be sealed and delivered.

I claim:

1. A top selecting mechanism including a vertical post, a horizontal arm extending therefrom, a delivery arm pivotally supported at an end of the said horizontal arm, a grapple on the end of said delivery arm remote from said horizontal arm, a vertically positioned rack bar within the said post, a horizontal rod having a rack gear enmeshed with the said rack bar within the said horizontal arm, the said delivery arm secured to the end of said rod remote from the said rack

gear, and means raising and lowering the said rack bar, turning the said rod and arcuately swinging the said delivery arm from delivering to receiving position.

5. A top selecting mechanism including a vertical post, a horizontal arm extending therefrom, a rack bar within the said vertical post, a rod within the said arm and having a rack gear enmeshed with the said rack bar, and an arcuately swinging delivery arm secured to the end of the said rod remote from the said rack gear, the said delivery arm having a suction cup at its end remote from its point of attachment to the said rod and horizontal arm.

15. 3. A top selecting mechanism including a vertical post, a horizontal arm extending therefrom, a rack bar within the said vertical post, a rod within the said arm and having a rack gear enmeshed with the said rack bar, and an arcuately swinging delivery arm secured to the end of the said rod remote from the said rack gear, the said delivery arm having a suction cup at its end remote from its point of attachment to the said rod and horizontal arm, the said suction cup being connected by a tube to a vacuum.

20. 4. In a top selecting mechanism including a hollow vertical post, a hollow horizontal arm extending from said post, a rack bar within the said post, a rod within said hollow arm and having on one end a rack gear enmeshing with the said rack bar, an arcuately swinging delivery arm secured to the said rod at its end remote from said rack gear, a container top chute positioned above the said delivery arm, and a suction cup secured to the end of said delivery arm remote from its point of attachment to the said rod.

25. 5. In a top selecting mechanism including a hollow vertical post, a hollow horizontal arm extending from said post, a rack bar within the said post, a rod within said hollow arm and having on one end a rack gear enmeshing with the said rack bar, an arcuately swinging delivery arm secured to the said rod at its end remote from said rack gear, a container top chute positioned above the said delivery arm, and a suction cup secured to the end of said delivery arm remote from its point of attachment to the said rod, the said delivery arm being swingable from a vertical delivery position to an approximately upright position in contact with a container top within the said chute.
